PAUL MERKLE, OF PHILADELPHIA, PENNSYLVANIA.

COIN-CONTROLLED DEVICE.

1,109,690.

Specification of Letters Patent.

Patented Sept. 8, 1914.

Application filed July 23, 1913. Serial No. 780,616.

To all whom it may concern:

Be it known that I, PAUL MERKLE, a citizen of the United States, residing at Philadelphia, in the county of Philadelphia and 5 State of Pennsylvania, have invented certain new and useful Improvements in Coin-Controlled Devices, of which the following is a specification.

My invention relates to coin-controlled devices adapted to receive a true coin and deliver it to an operating position and to reject false coins and prevent their delivery to the operating position.

The object of my invention is to provide 10 a coin-controlled device of novel, simple and efficient construction, having provision, first, whereby a true coin carried by a movable hand operated part or coin carrier may be delivered to the operating position in the 15 machine which the coin is to operate; secondly, whereby the coin carrier may be prevented from moving outwardly to its outward normal position after it has been moved inwardly a predetermined distance 20 with a coin and until the coin has been discharged from the carrier; thirdly, whereby false coins under a predetermined size may be prevented from reaching the said operating position; fourthly, whereby false 25 coins of magnetic metal may be prevented from reaching the said operating position; fifthly, whereby false coins having holes therein may be prevented from reaching the 30 said operating position; sixthly, whereby all false coins will be discharged into the machine to which my improved device is applied and will not be returned to the person 35 operating the device; and, seventhly, whereby various novel operations may take place, 40 all as will be hereinafter fully described and claimed.

In the accompanying drawings, illustrating my invention: Figure 1, is a side view of my improved coin-controlled device. 45 Fig. 2, is a horizontal section thereof, on line 2—2 of Fig. 1. Fig. 3, is a side view of the device with the front plate removed, showing the coin carrier in the outermost or normal position. Fig. 4, is a view similar 50 to Fig. 3, showing the coin carrier in the innermost position delivering a true coin to the operating position. Fig. 5, is a detail, showing a portion of the coin carrier and adjuncts. Fig. 6, is a detail, showing a false 55 coin being discharged from the coin carrier. Fig. 7, is a transverse section, on line 7—7 of

Fig. 3. Fig. 8, is a transverse section, on line 8—8 of Fig. 3. Fig. 9 is a transverse section, on line 9—9 of Fig. 3.

Referring to the drawings 3 designates a bracket or support adapted to be secured to the coin-operated machine in connection with which my device is to be employed. The bracket or support 3 is in the form of an elongated body, and secured to one side 60 thereof, by means of screws 4, is a face plate 5. Between the support 3 and plate 5 is a longitudinal bar 6 and a longitudinally movable plate 10, mounted to slide parallel to each other in suitable guideways formed in 65 and between the support 3 and plate 5.

The bar 6 constitutes the coin carrier, and one end thereof projects outwardly from the outer end of the support 3 and is adapted to be operated by hand to move the bar or carrier 6 from the outermost or normal position shown in Fig. 3 to the innermost position shown in Fig. 4 and back again. Formed in the side of the carrier 6 adjacent the plate 10 is a space or opening 11 75 adapted to receive a coin 12. One side of the opening 11 is closed by a wall of the carrier 6, and the other side of the opening 11 is normally closed by the adjacent face of the plate 10. When a true coin 12 is 80 within the opening 11 the coin is supported by and between a shoulder 13 formed on the carrier 6 and one end of a member 14 which is pivoted, at 15, on the carrier 6 and held normally in the position shown in Fig. 3 by 85 the guiding face formed on the bottom of an arm 16 which will be hereinafter referred to. When the carrier 6 is in the outermost position, the opening 11 is in registry with a slot 17 formed in the support 3 and 90 through which a coin may be inserted into the opening 11. The space between the shoulder 13 and member 14 is such that if a 95 true coin 12 be inserted, it will be supported as shown in Figs. 3 and 5, and that if a false coin of smaller diameter than a true coin be inserted, the false coin will fall through the space between the shoulder 13 and member 14 and from the support 3 through a false-coin slot 18 therein beneath 100 the carrier 6. When a true coin 12 has been inserted and the carrier 6 is pushed inwardly, the inward curved end of the member 14 will engage a beveled face 19 on the support 3 and move the member 14 on its 105 pivot 15 to lower the outer end thereof supporting the coin 12 and thereby free the coin.

12 and permit it to fall through a slot 20 in the support 3 to the devices to be operated thereby in the coin-operated machine in connection with which my device is used 5 and which it protects.

The coin-carrier 6 is provided with two projections 21 which extend into two longitudinal slots 22 in the adjacent plate 10 so that the plate 10 may be moved longitudinally with the carrier 6, and that lost motion between the carrier 6 and plate 10 may be had; that is to say, when the carrier is moved inwardly to the position shown in Fig. 4, the projections 21 will first traverse 10 the slots 22 and then engage the inner ends thereof and move the plate 10 inwardly to the position shown in Fig. 4; and that when the carrier 6 is moved outwardly from the position shown in Fig. 4 to the position 15 shown in Fig. 3, the projections 21 will first traverse the slots 22 and then engage the outer ends thereof and move the plate 10 outwardly to the position shown in Fig. 3. The plate 10 is provided with a coin-receiving 20 space or opening 23 which, when the projections 21 engage the inner ends of the slots 22, is in registry with the coin-receiving opening 11 in the carrier 6 and laterally thereof, as shown in Fig. 4, so that a coin 25 may move laterally from the opening 11 to the opening 23. In one position of the plate 10, when the openings 11 and 23 are in registry with each other, they come into registry with a horseshoe magnet 24 which 30 is supported on the face plate 5 outwardly of the slide plate 10, as shown. When the openings 11 and 23 come into registry with the magnet 24 and a false coin of magnetic metal is in the opening 11 in the carrier 6, 35 the magnet 24 will draw the false coin from the opening 11 in the carrier 6 into the opening 23 in the slide plate 10. The magnet 24 is located so that it will act to draw the false magnetic coin into the opening 23 40 before the carrier reaches the innermost position, shown in Fig. 4, thereby preventing the false magnetic coin from reaching the operative position in which it would fall from the device through the slot 20. After 45 a magnetic coin has been drawn by the magnet 24 into the opening 23 in the slide plate 10, and the carrier 6 is withdrawn to the position shown in Fig. 3, the magnetic coin is moved from the magnet 24, and the 50 bottom of the opening 23 comes over the false-coin slot 18 in the support 3, and the magnetic coin falls from the device through the slot 18.

I shall now describe the means for preventing washers therein from reaching the operating position and being discharged through the true-coin slot 20. The outward end of the arm 16 is pivoted, at 25, to the support 3, and the inward end of the arm 55 16 is held normally down in the position

shown in Figs. 3 and 4 by a spring 26 having one end secured to the support 3 and the other end secured to the arm 16. Arranged in horizontal slots in the face plate 5 are two dogs 27 and 28 which are pivoted, at 29 and 30, respectively, on vertical pins in a plate 31 secured to the plate 5. The free ends of the dogs 27 and 28 extend toward each other and they are pressed normally toward the carrier 6 by suitable springs 32 and 33, respectively, which are secured to the plate 31 and bear against the dogs. The free ends of the dogs 27 and 28 are adapted to extend through slots 34 and 35, respectively, in the slide plate 10 and to enter the coin-receiving opening 11 in the carrier 6 when the opening 11 passes or is moved into registry with the dogs. The dog 27 is adapted to enter the opening 11 in the carrier 6 above the center of a coin therein and the dog 28 is adapted to enter the opening 11 at or a slight distance below the center of a coin supported therein. The dog 27 extends from its pivot 29 in the direction of the inward movement of the carrier 6 and is adapted to ride over a coin or washer during inward movement of the carrier 6, and to engage a coin or washer and prevent it from moving with the carrier when the carrier is moved outwardly; and the dog 28 extends from its pivot 30 in the direction of the outward movement of the carrier 6 and is adapted to ride over a washer during outward movement of the carrier, and to engage a washer and prevent it from moving with the carrier when the carrier is moved inwardly. Now, if a washer, shown at 36 in Fig. 6, be inserted into the opening 11 and supported by the shoulder 13 and member 14, and the carrier 6 be moved inwardly, the free end of the dog 28 will enter the hole in the washer 36 and prevent inward movement thereof and also prevent inward movement of the carrier 6. When the carrier 6 is now moved outwardly the dog 28 will ride out of the hole in the washer 36, due to the location of the pivot 30 of the dog, and the free end of the dog 27 will enter the opening 11 below the top of the washer 36 and outwardly thereof, as shown in Fig. 6; and during the further outward movement of the carrier 6, the dog 27 will prevent the false coin 36 from moving with the carrier and will force the washer downwardly thereby moving the member 16 on its pivot 25 and the member 14 on its pivot 15 against the action of the spring 26, as shown in Fig. 6, until the washer 36 is freed and drops from the device through the false coin slot 18 in the support 3.

The coin-carrier 6 is prevented from moving outwardly beyond the position shown in Fig. 3, by the dog 27 entering a slot 37 in the member 14 and engaging the inner end of the slot; and inward movement of the car-

rier 6 is limited by the member 14 engaging the wall 19 and a pin 38 projecting from the carrier 6, as shown in Fig. 4.

When a true coin or a false coin of magnetic metal but of the size of a true coin is in the opening 11 and the carrier 6 is moved inwardly, the dog 27 rides over the face of the coin due to the location of the pivot 29 of the dog 27, and the dog 28 also rides 10 over the face of the coin as it is directed thereto by the face of the member 14 against which the dog 28 rests when the carrier 6 is in the outermost position, as shown in Fig. 2.

15 The coin-carrier 6 is provided with two similarly beveled portions 39 and 40 located one above the other and in alinement with the dogs 27 and 28, respectively, in the wall of the carrier 6 at the outer end of the coin-receiving opening 11, so that the dogs 27 and 28 may move into and from the opening 11 at the outer end thereof during either the inward or outward movement of the carrier 6.

25 My improved device hereinbefore described, is adapted to be secured to a coin operated machine by any suitable means and in such a manner that the outer or hand operated end of the carrier 6 will be exposed to be operated, and that a coin may be inserted into the slot 17 from the outside of the machine, and that all true coins passed through my device will be delivered to the slot 20 from which they will fall to 30 the operating parts of the machine, and so that all false coins passed through my device will be delivered to the false-coin slot 18 from which they will fall into a suitable receptacle within the machine.

35 40 I claim:

1. In a coin-controlled device, the combination of a support, a coin carrier movable on the support and having a coin-receiving opening therein provided with an open side, 45 a magnet on the support, a plate movable on the support between the carrier and the magnet and having a coin-receiving opening, and means for causing said plate to

move with said carrier and for permitting lost motion therebetween, said coin-receiving 50 openings coming into registry with each other adjacent said magnet when moved to one position, and said coin-receiving openings being away from said magnet and said plate closing the open side of the coin-receiving opening in the carrier when moved to another position, whereby when the said openings come into registry adjacent said magnet it may draw a magnetic coin from the opening in the carrier to the opening in 60 the plate, and whereby during a subsequent movement of the plate away from the magnet the magnetic coin may be discharged from the opening in the plate.

2. In a coin-controlled device, the combination of a support, a coin carrier movable on the support and having a coin-receiving opening therein provided with an open side, a magnet on the support, a plate movable on the support between the carrier and the 70 magnet and having a coin-receiving opening, and a pin projecting from said carrier and into a slot formed in said plate, said pin causing said plate to move with said carrier and said slot permitting lost motion between the plate and the carrier, said coin-receiving openings coming into registry with each other adjacent said magnet when moved to one position, and said coin-receiving 75 openings being away from said magnet and said plate closing the open side of the coin-receiving opening in the carrier when moved to another position, whereby when the openings come into registry adjacent said magnet it may draw a magnetic coin 80 from the opening in the carrier to the opening in the plate, and whereby during a subsequent movement of the plate away from the magnet the magnetic coin may be discharged 85 from the opening in the plate. 90

In testimony whereof I affix my signature in presence of two witnesses.

PAUL MERKLE.
